Primary Examiner — George D. Kirschbaum*Assistant Examiner* — Suzanne E Tisdell(74) *Attorney, Agent, or Firm* — Nixon & Vanderhye P.C.(57) **CLAIM**

The ornamental design for a battery box, as shown and described.

DESCRIPTION

FIG. 1 is a perspective view of a battery box according to an exemplary embodiment;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines shown in the figures represent portions of the battery box that form no part of the claimed design.

1 Claim, 6 Drawing Sheets(56)
